TRACK FOR SUPPORTING TRAVERSE DRAPES

Abram Samuels, Allentown, Pa.

Application December 2, 1955, Serial No. 550,550

5 Claims. (Cl. 16—95)

This invention relates to drapery hanging equipment, and particularly to track for supporting traverse drapes.

One of the problems present in the use of traverse drapery tracks is fouling of the operating cords. This is especially true of curved tracks, and has been primarily responsible for lack of acceptance of this type of track. Even in straight track cord fouling can be very annoying.

The principal object of the present invention is to provide a traverse drapery track which is so arranged that the operating cords will be left in orderly fashion at all times.

A more specific object is the provision of track having a cord-receiving trough to maintain the cord in proper position. Another object of the invention is to provide such track having means to support double-wheeled carriers for more balanced and smoother operation, particularly with curved track.

A further object is the provision of track which is symmetrical about its central vertical longitudinal plane, providing structural strength and a track which when straight is reversible and when curved may receive the carriers on either side.

Other objects of the invention will become apparent from the following description of one practical embodiment thereof when taken in conjunction with the drawings which accompany, and form part of, this specification.

In the drawings:

Figure 1 is a perspective view of a portion of track embodying the principles of the present invention, with the drapery carriers in place thereon;

Figure 2 is a side view of the track shown on a larger scale; and

Figure 3 is a vertical, transverse section through the track, taken on the line 3—3 of Figure 2.

In general, the invention concerns drapery-supporting track of particular cross-sectional design. Although the features of the track are specially adapted for curved track, the track is equally advantageous when formed as a straight track.

Referring to the drawings in detail, the track 1 is an elongated member, either curved in a horizontal plane or straight. The track is designed to have dual trackways 2 and 3 and a pair of troughs 4 and 5.

The cross-sectional shape of the track provides the various components mentioned above. The track in cross-section is essentially in the form of an I-beam having top and bottom flanges 6 and 7 and a central, vertical, interconnecting web 8. The track is shown as having substantially the same width as height, but these relative dimensions are not essential.

The trackways 2 and 3 and the troughs 4 and 5 are formed by additional vertical webs 9 and 10, each extending upwardly from the bottom flange 7 of the I-beam midway between the central web 8 and the outer edges of the bottom flange. The webs 9 and 10 terminate just above halfway between the flanges 6 and 7, and horizontal flanges 11 and 12 project outwardly from the tops

2

of the webs parallel to the flanges of the I-beam. Thus, there are formed two outwardly opening channels which serve as the trackways 2 and 3. These are at the outer lower edges of the I-beam, with the troughs 4 and 5 behind them between the vertical webs 9 and 10 and the central web 8. The spaces between the flanges 11 and 12 and the top flange 6 of the I-beam serve as entrance throats to the troughs.

The track will receive a master carrier and as many single carriers as may be required to adequately support and control the drapery to be hung. The master carrier will consist of two spaced, U-shaped members 13 connected and held in spaced relation by a connecting bar 14 secured to the bases of the U-shaped hangers 13. The vertical legs of the U-shaped members carry rollers 15 and 16, offset inwardly to ride in the trackways 2 and 3. The base of the U-member may have turned down stiffening flanges 17 and 18 at the sides if desired. Midway between the U-members, an arm 19 is attached to the connecting bar 14. Arm 19 extends upwardly at the side of the carriage and is bent at a right angle to extend inwardly above the horizontal flange 12 to project into the throat leading to trough 5. A cord-attaching member 20 depends into the trough from the inwardly extending portion of arm 19. An operating cord 21 lies within the trough and is connected to the cord-attaching member 20. It will be obvious that movement of the cord will cause movement of the master carrier. The master carrier is provided with an eye 22 to which the drapery may be secured.

The single carriers consist of but one U-shaped member 23, to which are attached the wheels 24. An eye 25 is connected to the bottom of the U-member to hold the drapery.

It will be seen that the cross-sectional shape of the track provides for compactness, maintains the cord in proper position to prevent tangling whether the track is straight or curved in part or throughout its length. It will be obvious that the master carrier may be put on the track so that the cord-attaching arm will be in either trough 4 or trough 5.

While in the above one practical embodiment of the invention has been disclosed, it will be understood that the details of the structure shown and described are merely by way of illustration and changes may be made within the scope of the appended claims.

What is claimed is:

1. A track for supporting traverse draperies comprising, an elongated member having a pair of vertically spaced horizontal flanges, a central vertical web interconnecting said flanges midway between the side edges of said flanges, additional vertical webs one on each side of said central web spaced from said central web and the respective side edges of the lower of said horizontal flanges and extending upwardly from the lower of said horizontal flanges and terminating short of the upper of said horizontal flanges, and horizontal flanges extending from the tops of said additional webs outwardly to the vertical planes including the side edges of said first-mentioned horizontal flanges whereby carrier trackway channels are formed at each side with carrier operating cord troughs behind each channel with an entrance throat to each trough above each channel.

2. In a track as claimed in claim 1, master-carriers and single carriers, each consisting of U-shaped frames with rollers mounted on the inner sides of the legs of the U-shaped frames and adapted to ride on the lower of said first-mentioned horizontal flanges between the side edges thereof and said additional vertical webs, and said master-carrier having an arm joined to the U-shaped frame adapted to project into one of the cord troughs between said central vertical web and said additional ver-

tical webs for attachment to a control cord adapted to lie within said trough.

3. In a track as claimed in claim 2, said elongated member and said trackway channels being curved transversely from end to end.

4. A track for cord operated rollered carriers comprising, an elongated member of I-beam cross-section having horizontal lower flanges, inverted L-shaped members having their vertical legs mounted intermediate the lower flanges to provide spacing of each vertical leg from the web of the I-beam member and their horizontal legs directed outwardly to form outwardly opening roller-receiving channels on either side of the I-beam member, said spacing of each vertical leg from said web of the I-beam member forming troughs therebetween to receive operating cords for said carriers, and said horizontal legs of said inverted L-shaped members being spaced from the upper flange of said I-beam member to provide a passageway for insertion of said cords into said trough.

5. A track for rollered carriers designed to support 20 traverse draperies comprising, an elongated member of

I-beam cross-section with outwardly opening roller-receiving channels on either side of the I-beam member and having their bases formed integrally with the bottom flanges of the I-beam member, said channels being spaced horizontally from the central vertical web of the I-beam member, whereby carrier operating cord-receiving troughs are formed behind each channel, and said channels having their outwardly extending tops spaced below the top flanges of the I-beam member providing 10 passageways into the cord-receiving troughs between the outwardly extending tops of the channels and the top flanges of the I-beam member.
